UNITED STATES PATENT OFFICE.

ALFRED W. STORM, OF RAMSEY, NEW JERSEY, ASSIGNOR OF ONE-TENTH
TO THOMAS S. CRANE, OF EAST ORANGE, NEW JERSEY.

FRANGIBLE SEAL AND NOZZLE FOR BOTTLES.

SPECIFICATION forming part of Letters Patent No. 582,322, dated May 11, 1897.

Application filed January 22, 1896. Serial No. 576,417. (No model.)

To all whom it may concern:

Be it known that I, ALFRED W. STORM, a citizen of the United States, residing at Ramsey, Bergen county, New Jersey, have invented certain new and useful Improvements in Frangible Seals and Nozzles for Bottles, fully described and represented in the following specification and the accompanying drawings, forming a part of the same.

10 The object of this invention is to furnish a construction for hermetically securing liquids in glass bottles and to facilitate the breaking of such seal and the use of the contents when the bottle is broken. To facilitate the her-
15 metic sealing of the bottle, the neck is re-
duced abruptly to a nozzle of materially
smaller diameter and less in strength than
the neck of the bottle, by which construction
the tip of the nozzle can be melted in a blow-
20 pipe-flame with very great despatch and a low
degree of heat.

By making the nozzle materially smaller
25 than the neck it is adapted to furnish a most
convenient spout for pouring the contents, if
valuable or corrosive, into other bottles or re-
ceptacles without any spilling or dripping of
the fluid, and it may also be readily broken
30 after it is hermetically sealed. A nick is prefer-
ably made in the base of the nozzle to deter-
mine the point of breakage.

By making the nozzle materially smaller
35 than the neck it possesses but little strength
and thus requires protection in transporta-
tion, and I therefore form the neck of the bottle
below the contracted portion with a suitable
40 seat and apply a detachable cap to the same
to cover and protect the nozzle. The cap also
serves to prevent the evaporation of the bot-
tles contents after the nozzle is broken and
45 before the contents are entirely removed.
When the nozzle is thus sealed and protected
by a cap, the bottle forms a sealed package
which can be safely transported and whose
age.

By forming a nick upon the side of the noz-
zle near its junction with the neck it is read-
ily adapted to fracture transversely, so as to
form an efficient spout; but the shortness of
50 such nozzle if it be resealed by melting the
glass distinguishes it clearly in appearance

from the original nozzle and thus shows that
the bottle is not an original package.

The initial length of the nozzle (which may
be made uniform, so as to become known to 55
the public) or the nick upon the same, which
is destroyed in opening the bottle, thus serves,
when present, to guarantee the genuineness
of the bottle's contents.

To facilitate the filling or emptying of the 60
bottle through a relatively small nozzle, the
bottle-neck is preferably formed with another
nozzle to serve as an air-vent, and I have
shown such a construction in the annexed
drawings, in which—

Figure 1 is a side elevation of the bottle,
(broken transversely for want of room in the
drawing,) with a cap fitted to a screw-thread
upon the neck of the bottle, and one of the
nozzles, as well as the cap, being shown in 70
section at the center line where hatched.
Two nozzles are shown upon the bottle in
Fig. 1; and Fig. 2 represents the neck of the
same bottle with the nozzles broken in readi-
ness to use the contents. Fig. 3 represents 75
the neck of a bottle with a conical ground
seat and the nozzle in its unsealed condition.
Fig. 4 represents such bottle-neck with the
nozzle sealed and a cap fitted to the ground
seat. Figs. 3 and 4 may be taken to repre- 80
sent a bottle-neck provided with a single noz-
zle, or with two nozzles, as in Fig. 1, viewed
laterally, so that one nozzle would hide the
other. A dotted curve c is shown in Fig. 4
to represent the depression between the noz- 85
zles, which is apparent in Fig. 1.

A is the body of the bottle, B the neck of
the same, and C C' the nozzles extended up-
ward from the neck. The neck is tapered
upwardly into the base of each nozzle, so that 90
an edge view of the two nozzles, which are
represented in Fig. 1, would appear the same
as the view of the single nozzle shown in Fig.
4, and the top of the neck just below the ta-
pering portion is provided with a screw-thread 95
D, Figs. 1 and 2, or conical ground seat D', as
in Fig. 4.

A metallic cap E is shown fitted to the
screw-thread D and extended over the noz-
zles C C' in Fig. 1, and a glass or vitreous cap 100
E' is shown fitted to the ground seat D' in Fig.
4 and extended over the nozzle. Such nozzle

is lettered C², as it may, differently from Fig. 1, designate a single nozzle upon the bottle-neck, and the nozzle in Fig. 3 is designated C³, as it represents the unsealed nozzle or nozzles when first made by the glass-blower in readiness for filling the bottle and subsequent sealing. A nick F is shown upon each sealed nozzle transversely across the same near its junction with the neck B, and such a nick is readily formed after the nozzle is sealed by means of a file or diamond, and produces a square fracture across the tube of the nozzle when the latter is struck laterally above the nick.

15 The nozzles being much weaker than the neck of the bottle require the protection of the cap E or E' during transportation before the bottle is opened, while the construction of the nozzle and its neck is exactly adapted to facilitate the opening of the package by a light blow upon the nozzle, which may be effected with a lead-pencil, penknife, or any other agent, requiring much less force than the extraction of a cork.

25 The cap E or E' is made of suitable height to inclose the nozzles in their initial condition; but it is obvious that the nozzles, if resealed after they are broken off, as shown in Fig. 2, would not project anywhere near to 30 the top of the cap.

Any one familiar with the initial appearance of such nozzles—that is to say, with their ordinary length when first sealed and the visible nick F upon the side of each—35 would readily discover that the bottle had been tampered with if it were exhibited to him with the broken nozzles resealed; and the construction thus furnishes an effective means of preventing the fraudulent refilling 40 of bottles, and without the use of any mechanism or valve fixtures of any kind.

In filling the bottle with single neck the filling-tube would be made small enough to pass downward through a single nozzle, the 45 space between the tube and nozzle permitting the air to escape, but where two nozzles are provided the liquid is introduced or removed from one and the other furnishes an air-vent, which permits a very free and rapid 50 movement of the liquid.

My invention may be practiced with a bottle of any suitable vitreous material adapted for hermetically sealing by the use of a flame or blowpipe applied to the tip of the nozzle.

55 The whole device, when sealed, constitutes a sealed liquid-package in which the contents are hermetically inclosed and the nozzle protected from accidental injury.

I am aware that bottle-mouths have been 60 sealed by fusion and by welding glass caps upon the same, and I do not, therefore, claim the mere hermetical sealing of a bottle by such means. A nick formed in the side of a bottle-neck is not, as experience shows, capable 65 of insuring a perfect fracture across the neck of the bottle when struck to break off the same, as the strength of an ordinary bottle-

neck is such as to require considerable force to fracture it.

I am aware that detachable caps have been used upon bottles having open necks, as in receptacles for mucilage, syrups, and liquors; but I am not aware that a detachable cap has ever been employed to protect a nozzle hermetically sealed with a delicate point which 75 would be readily injured by concussion, and the cap thus performs a special function in protecting a nozzle which is made of much smaller diameter than the bottle-neck, so that it will be much weaker relatively than the 80 neck.

I am aware that it has been proposed to weld glass buttons, disks, and caps of various kinds upon a bottle-neck, but my construction differs essentially from this in closing 85 the outlet to the neck itself and in facilitating such closure with a blowpipe by forming the neck with an abruptly -reduced nozzle. I hereby disclaim the mere use of a cap or the use of fusion for hermetically sealing a bot- 90 tle-neck, as my invention involves the abrupt reduction of the neck to form the nozzle and the arrangement of the seat upon the unreduced portion of the neck below the base of the nozzle.

95 The advantages of my invention will be apparent from the fact that the strength of the nozzle varies with the square of the diameter if of the same thickness as the neck; but as it would not need to be more than one-half 100 of the thickness of the neck it may be broken with one-eighth or one-sixteenth of the force required to sever the neck. The same proportion holds good in regard to the heat required to seal such nozzle, and not more than 105 one-eighth or one-sixteenth of the heat would be required that would be necessary to fuse the neck of the bottle, and my device thus furnishes a very economical seal and the most 110 convenient and effective means of breaking the same, while preserving a practicable spout for future use upon the bottle.

If the nozzle were tapered materially from its base toward its point, it would be stronger at the base than at any intermediate place 115 and would be more difficult to fracture at a given point. I therefore make the nozzles parallel, as shown in Figs. 1, 3, and 4, by which construction a lateral blow upon the nozzle tends, by its leverage, to break it off 120 as square as possible to the base, and a nick formed adjacent to the base thus readily determines the point of fracture.

125 It will be noticed that the tendency of the nozzle to fracture without injury to the neck of the bottle is greatly enhanced by reducing the bottle-neck abruptly, as shown in the drawings, to form the projecting nozzle, so that a very considerable difference in the relative strength of the neck and nozzle is produced within a very short distance, which determines with more certainty the point where the nozzle is liable to break when struck laterally.

It will also be understood that the nick when formed near the base of the nozzle, as shown in Fig. 1, lies intermediate to the strong or unreduced portion of the bottle-neck and the 5 projecting nozzle, which is materially smaller than the neck, so that the portion below the nick is much stronger than the portion above the nick. The nick thus lies in the best position to facilitate a transverse fracture of 10 the nozzle, as the portion below the nick is of so much greater strength than that above the same that a lateral blow upon the nozzle has no tendency to break or shatter the portion below the nick. I have therefore claimed 15 a lateral nick upon the nozzle in this relation to the bottle-neck where its dimensions are reduced to form the nozzle.

Having thus set forth the nature of my invention, what I claim, and desire to secure by 20 Letters Patent, is—

1. A sealed liquid-package comprising a vitreous bottle having the neck reduced abruptly near the top to an integral contracted nozzle of parallel tubular form with hermetically-sealed end, the nozzle being materially less in strength than the neck and provided 25 near the base with a transverse nick to determine the point of fracture, and the neck being provided below the contracted portion 30 with a seat to receive a cap, and a cap fitted detachably to the seat to cover such nozzle and protect the point from injury, the whole

arranged and operated substantially as herein set forth.

2. A sealed liquid-package, comprising a 35 vitreous bottle having a neck extended into two reduced nozzles, said nozzles being hermetically sealed and provided each with a transverse nick to facilitate breakage, and a cap being fitted detachably over the nozzles 40 and secured upon the neck by a suitable tight joint, the cap performing the double function of protecting the nozzles until broken, and thereafter preventing the evaporation of the bottle's contents, as and for the purpose set 45 forth.

3. As a new article of manufacture, a vitreous bottle having the neck provided with a screw-thread and extended into two reduced nozzles of suitable length to be hermetically 50 sealed and fractured transversely without injury to the bottle-neck or thread, such nozzles serving respectively as an inlet and outlet in filling or discharging the bottle, and the thread being adapted to receive a detachable cap, substantially as herein set forth.

In testimony whereof I have hereunto set my hand in the presence of two subscribing witnesses.

ALFRED W. STORM.
